GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR CONNECTER.

Application filed September 13, 1919. Serial No. 323,594.

To all whom it may concern:

Be it known that I, GEORGE M. EATON, a citizen of the United States, and a resident of Pittsburgh, in the county of Allegheny and State of Pennsylvania, have invented a new and useful Improvement in Insulator Connecters, of which the following is a specification.

My invention relates to connecters and particularly to connecters employed in series-related strain and suspension insulator sets.

One object of my invention is to provide a device of the above indicated character that shall occupy a small amount of axial space in an insulator set or other device in which it may be used and that may be conveniently connected and disconnected by the manipulation of a single member only.

Another object of my invention is to provide a connector comprising relatively-simple, strong and durable self-locking parts that are not likely to deteriorate through wear and weather and that shall permit the installation or substitution of a damaged insulating member of a series set in a minimum amount of time and by the manipulation of a minimum number of easily-handled parts.

Heretofore, in series-related strain and suspension insulators, and particularly in those in which the insulating members are of the disc type and usually connected by flexible cable loops, difficulty has been encountered in satisfactorily and efficiently connecting the cables.

Difficulty has heretofore been encountered in manipulating the connecters that have been usually employed or, as an alternative, the insulating members have been spaced apart in excess of service requirements.

In outdoor line construction, it is imperative that construction and repair operations be facilitated to the utmost by reason of weather conditions and other hazards that are encountered. The manipulation of nuts, screws and other small parts becomes almost impossible under certain conditions and it is, therefore, highly desirable, if not absolutely necessary, to eliminate these and render all operations simple and effective.

In practicing my invention, I provide a connector that is reduced to occupy substantially a minimum amount of space between the several members of an insulator

set. This is effected by having the connector parts relatively narrow and disposed transversely with respect to the longitudinal axis of the insulator.

Further, the parts are of such simple interfitting construction and are so provided with a simple transversely-operable wedge-connecting member as to provide easier access to, and manipulation of, the connector members of a strain or suspension insulator set than has heretofore been usual in similar sets having greater distances between the members thereof.

Figure 1 of the accompanying drawings is a side view, partially in elevation and partially in section, of an insulator and connectors embodying my invention; Fig. 2 is a plan view of a partially assembled connector; Fig. 3 is a detail view of parts of a connector after it has been assembled; Fig. 4 is a detail view of a modified form of pin or wedge therefor and Fig. 5 is a detail view of a portion of the device, taken in the direction of an arrow V, in Fig. 3.

My device comprises, in general, a plurality of insulator units 1 each comprising an insulating member 2 that has metal connecting members 3 permanently attached to each end thereof, members 4 and 5 for attachment to opposite ends of a series of the units 1 and wedges 6 for attaching the units 1 to each other and a series of the units 1 to the members 4 and 5.

The insulating members 2, preferably of porcelain and of the disc type, are provided with angularly-related transverse curved openings 7 for the reception of interlinked, preferably yieldable, metal members 8 having ends 9 projecting oppositely from the members 1.

The members 8 comprise complementary half-round or semi-circular cable or connector portions 10, the outer ends 9 of which extend through tapered openings 11 in transverse metal members 12 and have swaged portions 13 projecting over the ends of metal wedges 14.

The members 12 are identical and interchangeable and of substantially yoke-shape having relatively-thin flat transverse mid-portions 15 and integral legs or hubs 16 extending in the direction of the axis of the insulator and having the openings 11, as described.

All of the units 1 of a series are identical,

the members 8 and 12 of the members 3 being attached to each end of each insulating member 2, but the two opposite members 12 of each unit are angularly displaced substantially 90°, with respect to each other, about the longitudinal axis of the insulator.

When assembled, all of the units 1 are substantially symmetrically positioned with respect to the longitudinal axis of the insulator; that is, the members 3 at each end of each unit are each placed in the same angular relation about the longitudinal axis of the insulator as the corresponding members 3 of the other units. This places the members 12 between each pair of the members 2 in the proper crossed relation for locking.

At the extreme ends of the series of units 1, the members 4 and 5 mate with the adjacent members 12 and are provided with means, such as bolts 17 and members 18, for attachment to a supporting structure 19 and to a current-carrying line 20, respectively.

The units 1 being all in the same angular position with respect to the longitudinal axis of the insulator, any number of the same can, therefore, be placed in series and have the extreme end members 12 in proper position for mating with the members 4 and 5.

Between the members 2 of each pair, two of the members 12 are disposed in proximate crossed relation, with the mid portions 15 close to each other, in substantially right-angled relation, and the hubs 16 of each member 12 facing the other and projecting into a common transverse zone therewith.

Each member 12 has portions 21, projecting laterally with respect to the mid portion 15, at certain ends of which a groove 22 and a tongue 23 are respectively adapted to register and interfit with the tongue 23 and the groove 22 of the correlated member 12. Certain other of the portions 21 of each member 12 are provided with wedge or pin-receiving grooved portions 24 and 25 which are, respectively, adapted to co-operate with the portions 24 and 25 of the complementary member 12 to receive the tapered pin or wedge 6 that may be wedgingly maintained in operative position or be bent or otherwise secured after its insertion.

As shown in Fig. 4, the wedge 6 is formed circular in cross section and has a longitudinal split portion, at its smaller end, that may be opened, as indicated in dotted lines, to prevent the withdrawal of the wedge. In case of the employment of a wedge of this type, the grooves 24 and 25 will be modified to conform to the wedge.

The assembly of the units 1, each comprising the members 2, 3 and 12, is preferably a bench operation, whereby a plurality

of readily-transportable and conveniently-mountable insulator units are constructed which may be installed or renewed with great facility, the simple and convenient wedge or pin 6 being the only extra or loose part.

All of the metal parts are preferably of sherardized, or otherwise rust-proofed, malleable iron or steel or they may be constructed of non-rusting material, such as brass. This ensures effective co-operation of the members, prevents deterioration and facilitates their assembly.

When connecting two of the units 1, the co-operating members 12 of each are placed in the position illustrated in Fig. 2. The members 12 are here shown as displaced from their final locked position angularly, relative to the longitudinal axis of the insulator but are in the proper longitudinal position to effect, in the next operation, the final registry of the grooves 22 and the tongues 23 and the wedge-receiving portions 24 and 25, respectively.

Each member 12 is of substantially H-shape having the mid portion 15 as its cross portion and the portions 21 as its side legs. The members 12 are assembled by being placed together laterally with the mid portions 15 crossed at substantially right angles to each other. This relation places the portions 21, that constitute the side legs of the H, in end to end relation, thereby substantially constituting a hollow square with the mid portion 15 crossing each other normal to the sides.

In the final locking position, while the mid portions 15 are crossed, they are spaced apart to admit the wedge 6 therebetween. The tongue 23 and groove 22 are accordingly positioned to register when the mid portions 15 are, thus, separated. Ordinarily the portions 15 may be placed in cross relation and engaged but, when so engaged, they must be withdrawn until the tongue 23 and groove 22 are in register.

To facilitate the proper spacing of the members 12, in the direction of the longitudinal axis of the insulator, the walls 26 and 27 of the groove 22 are constructed to project different distances from the bottom of the groove. The wall 26 projects beyond the wall 27 and the tongue 23 is, correspondingly, formed longer on one side than on the other to assist in finding this position before the wedge is driven home.

Relative movement of the members 12, about the longitudinal axis of the insulator may be effected to place the tongues 23 partially in the grooves 22 and space the portions 24 and 25 to receive the wedge 6, or, since the wedge is relatively smaller in cross-section at its entering end and the bottom of the grooves of the portions 25 are sufficiently spaced at all times to permit

the ready insertion of the wedge, the movement may be entirely effected when the wedge is inserted. The wedge 6, in operative position, extends diagonally with respect to both of, and between, the mid portions 15.

The device is constructed to occupy substantially a minimum of axial space with respect to the members 1, thereby permitting the latter to be placed relatively close together and reducing the overall length of a series insulator set. Further, by reason of the ease and facility with which the wedge may be inserted and withdrawn from operative position, the time and labor required to manipulate the device are greatly reduced, thus minimizing the hazards to the linemen and lessening the inconveniences caused by damaged insulators.

20 While I have shown and described a particular form of my invention, changes may be effected therein without departing from the spirit and scope thereof, as set forth in the appended claims.

25 I claim as my invention:

1. A connector for a series-string suspension insulator comprising two relatively flat crossed members disposed in proximate parallel planes transversely to the longitudinal axis of the insulator to permit the units of the latter to be placed close to each other, said members having offset co-operating tongue-and-groove connecting portions and co-operating offset portions for the reception of a wedge, and a wedge extending diagonally of the crossed members in said wedge-receiving portions.

2. An insulator connector comprising co-operating members for attachment to adjacent insulator units, said members having tongue-and-groove and wedge-receiving portions extending transversely to the longitudinal axis of the insulator, and a wedge for positioning in said wedge-receiving portions, said members being adapted for angular relative movement about said axis to interfit the tongue-and-groove portions when the wedge is driven home.

3. A connector for a series-string suspension insulator comprising two relatively flat crossed members disposed in proximate parallel planes transversely to the longitudinal axis of the insulator and each having means at each end for attachment to members extending parallel to said axis, substantially T-head portions at the ends of each of said crossed members arranged in the form of a square of which the crossed members are diagonals, said T-head portions having tongue-and-groove connections between two pairs of the ends thereof and tapered

grooves in two other pairs of the ends thereof, and a tapered wedge for positioning in the grooves of said last pair of T-head portions.

65

4. An insulator connector comprising two elongated crossed members, extending transversely of the longitudinal axis of the insulator, having laterally-extending interfitting portions at diametrically opposite ends thereof and means for securing said portions in binding co-operative relation.

5. An insulator connector comprising two elongated members disposed in proximate crossed relation transversely to the longitudinal axis of the insulator, said members having laterally-extending interfitting portions, and means co-operating between the outer ends thereof for holding said members together.

75

6. An insulator connector comprising two members disposed in proximate parallel planes transversely to the longitudinal axis of the insulator and having co-operating portions projecting into a common zone therebetween wherein a relative movement of said members about said axis places said portions in co-operative holding relation, and a single means for holding said members together.

80

7. An insulator connector comprising a pair of members having co-operating tongue-and-groove portions extending transversely to the longitudinal axis of the insulator and co-operating wedge-receiving portions, and a wedge co-operating with said receiving portions to hold the tongue-and-groove portions together.

95

8. An insulator connector comprising a pair of members having co-operating tongue-and-groove portions extending transversely to the longitudinal axis of the insulator and similarly extending co-operating wedge-receiving portions, and a wedge co-operating with said receiving portions to hold the tongue-and-groove portions together.

100

9. An insulator connector comprising a pair of members having co-operating tongue-and-groove portions extending transversely to the longitudinal axis of the insulator and adapted to be placed in adjacent inoperative relation, said members also having co-operating wedge-receiving portions, and a wedge co-operating with said receiving portions to move the tongue-and-groove portions into operative relation and to hold the members together.

110

In testimony whereof, I have hereunto subscribed my name this 29th day of Aug. 1919.

GEORGE M. EATON.
